Inventor

UNITED STATES PATENT OFFICE.

CHARLES A. BERG, OF MAPLE SHADE, NEW JERSEY.

SHOE-PROTECTOR.

1,053,555.

Specification of Letters Patent. Patented Feb. 18, 1913.

Application filed February 20, 1912. Serial No. 678,838.

To all whom it may concern:

Be it known that I, CHARLES A. BERG, a citizen of the United States, residing at Maple Shade, in the county of Burlington 5 and State of New Jersey, have invented certain new and useful Improvements in Shoe-Protectors, of which the following is a specification.

My invention relates to improvements in 10 shoe protectors, the object of the invention being to provide a device of this character which may be easily and quickly placed in position on a shoe and which will protect the shoe from paint, plaster, or other matter which might fall thereon.

A further object is to provide a device of 15 this character described which will fit any shoe and which will hold itself in position on the shoe without the employment of straps of any sort.

With these and other objects in view, the invention consists in certain novel features of construction and combinations and arrangements of parts as will be more fully 20 hereinafter described and pointed out in the claims.

In the accompanying drawings: Figure 1, is a perspective view illustrating my improvements in position on a shoe. Fig. 2, is 25 a plan view of the device lying flat. Fig. 3, is a view in cross section of the device in operative position. Fig. 4, is a perspective view of the wire spring 4, and Fig. 5, is a view in section on the line 5—5 of Fig. 2.

My improved shoe protector comprises 30 two half sections 1 and 2 preferably of oil cloth or other flexible waterproof material, which may be cleaned from time to time as desired. The half sections overlap, as 35 shown, and are connected by an elastic strip 3 which permits the sections to be moved relative to each other to fit different sizes of shoes.

A wire spring 4 conforming in shape to 40 the shape of a shoe where the upper joins the sole of the shoe, is secured to the protector adjacent its outer edges. The wire, except at its ends, is confined in a folded portion 5 of the protector, and secured by

lines of stitching 6. It will be noted, however, that the protector extends beyond the spring wire, so as to extend over the sole of a shoe and protect it from paint and the like. The ends of the wire spring which project beyond the rear end of the protector 55 are bent forming finger holds 7, so that they may be readily grasped to spread the spring and release the protector from the shoe.

On the rear end of one section 2, a hook 8 is pivotally secured by a rivet 9, and is 60 adapted to engage the shoestring of a lace shoe, or the button hole of a button shoe to hold the device against forward movement on the shoe.

To place the protector on a shoe, it is 65 simply necessary to catch the hook 8 on the shoestring or in the button hole and then grasp the finger holds 7 spreading the spring wire and positioning it around the shoe just above the sole. When the spring 70 wire is released, it will tightly grip the shoe and hold the protector thereon.

As the ends of the wire extend around under the instep of the shoe, the hand holds are out of the way, but can be readily 75 reached to release the device from the shoe.

The elastic strip 3 draws the sections 1 and 2 toward each other, so as to snugly fit over any size shoe.

It is of course to be understood that the 80 device is to be made and sold in pairs, and the invention is not limited to the precise details set forth, but I consider myself at liberty to make such changes and alterations as fairly fall within the spirit and scope of 85 the appended claims.

Having thus described my invention, what I claim as new and desire to secure by Letters Patent is:

1. A shoe protector consisting of a covering 90 comprising two overlapping sections, elastic means connecting the sections, and means constructed to hold the covering on a shoe, substantially as described.

2. A shoe protector, consisting of a cover- 95 ing comprising two overlapping sections of flexible material, a spring wire secured in the overlapping edges of the covering and

adapted to clamp around the toe portion of a shoe above the sole thereof, finger holds on the ends of said spring wire, said covering comprising two overlapping sections, 5 and an elastic strip connecting said sections, substantially as described.

In testimony whereof I have signed my

name to this specification in the presence of two subscribing witnesses.

CHARLES A. BERG.
